CHEMICAL HEATING PAD FOR PERMANENT HAIR WAVING

Frederick L. Reynolds, Mill Valley, Calif., assignor, by mesne assignments, to United States Appliance Corporation, San Francisco, Calif., a corporation of California

Application November 24, 1937, Serial No. 176,229

4 Claims. (Cl. 132—36.2)

This invention relates generally to the construction of so-called chemical heating pads, particularly pads suitable for carrying out heating operations in permanent hair waving.

5 Chemical heating pads, such as are suitable for permanent hair waving, make use of an exothermic reaction between certain chemicals, to furnish sufficient heat for a waving operation. The type of pad employed for this purpose in the 10 past has made use of a metal foil envelope or sachet, containing the necessary chemicals in dry powdered or granular form. In using such a pad the envelope is perforated and the chemicals moistened with water, immediately before applying the pad about a wound strand of hair. Pads of this kind are subject to several serious disadvantages. They are relatively expensive to manufacture, because of the use of metal foil envelopes or sachets containing the powdered chemicals. 15 They are subject to relatively rapid deterioration when exposed to the air, due to more or less absorption of moisture from the atmosphere, with the result that some or all of the chemical action takes place before the pads are used. Because 20 of such deterioration it is common to supply pads to the trade in relatively expensive sealed containers. However, even with this practice the pads are subject to deterioration, with the result that the performance obtained is erratic. 25 It is an object of the present invention to provide a simple chemical heating pad, suitable for permanent hair waving, characterized particularly by the absence of chemicals in powdered or granular form, within a foil envelope. In carrying 30 out the present invention the reaction elements consist of a sheet of reactive metal like aluminum, in conjunction with a solution containing chemicals capable of exothermic reaction with the aluminum. The solution is carried by a sheet 35 of absorbent material, to which it can be applied immediately before a waving operation.

A further object of the invention is to provide a chemical heating pad suitable for permanent hair waving, which will not deteriorate in any way when stored over long periods of time, even though exposed to the atmosphere.

Further objects of the invention will appear from the following description in which the preferred embodiment of the invention has been set forth in detail in conjunction with the accompanying drawing.

Referring to the drawing:

Fig. 1 is a perspective view, illustrating a pad 55 incorporating the present invention, and showing

the manner in which chemical solution is applied to the same.

Fig. 2 is a perspective view, illustrating the manner in which the pad can be folded after application of chemical solution. 5

Figs. 3 and 4 are plan views illustrating how the marginal edges of the outer wrapper can be folded over to form a packet, shown in complete form in Fig. 4.

Fig. 5 is a greatly enlarged cross-sectional detail, 10 illustrating the manner in which the aluminum foil and associated sheets of absorbent asbestos, are perforated.

Fig. 6 is an enlarged cross-sectional detail taken along the line 6—6 of Fig. 1, and showing a 15 simple form of attachment to the outer foil covering, and a stitching which can be used for retaining the sheets of asbestos material assembled with respect to the aluminum foil.

Fig. 7 is an end elevational view partly in cross- 20 section showing the pad as applied to a hair curler and held in place by a suitable clamp.

Referring to the embodiment of the invention illustrated in the drawing, I have shown a pad consisting of an inner assembly 10, together with 25 an outer covering 11. The assembly 10 consists of a sheet 12 of aluminum foil, between two sheets 13 of absorbent material. The sheets 13 are of non-inflammable material, such as an absorbent asbestos paper. The thickness of the aluminum 30 foil 12 may vary depending upon different requirements or conditions, but in practice I have used a gauge of about .0015 inch, with good results. The surfaces of the aluminum foil can be cleaned, as by means of a suitable cleansing 35 reagent. While sheets 13 may vary in weight, six pound asbestos paper will give good results.

The assembly 10 is retained together by suitable means, such as two rows of stitching 14, extending along the side margins. After forming 40 this assembly it is passed through a suitable perforating appliance, whereby the perforations 16 are formed over the entire area of the assembly. It will be noted from enlarged Fig. 5 that the perforations 16 extend through the entire assembly, so that in effect the openings in the individual sheets of asbestos and aluminum foil, are in registry. Also it is preferable to form these perforations by piercing needles, so that there is no punching out of material, such as 45 would decrease the effective reactive surface and mass of the aluminum foil.

The covering 11 can consist of a sheet of aluminum or tin foil 17, provided with an inner liner 18 of suitable material such as waxed or parch- 50

- ment paper. Such a liner affords a chemically inert membrane, to prevent reaction between the chemical solution and the foil covering 17. The inner assembly 10 can be secured to the covering 11 by suitable means, such as the wire attaching elements 21. In a pad of the type illustrated it is desirable that this attachment be made near one end of the assembly 10, and near one marginal edge of the covering 11.
- 10 In making use of the pad described above a suitable chemical solution must be provided, to saturate the asbestos sheet 13. Solutions which I can employ contain chemicals such as a salt of a heavy metal, like copper sulphate, capable of exothermic reaction with aluminum, together with an oxidizing reagent like sodium chlorate, to prevent polarization, and a salt like aluminum sulphate tending to speed up commencement of the steaming period. An example of a chemical 20 solution which can be employed with good results, is as follows:—

Hydrated copper sulphate	grams	3
Sodium chlorate	do	15
Hydrated aluminum sulphate	do	1/2
25 Ammonium chloride	do	1/2
Sufficient water to make 30 cc. of solution.		

The ammonium chloride initially activates the reaction and depresses the pH value of the solution. As the reaction of the solution on the aluminum proceeds, and the solution is heated to an elevated temperature, some decomposition of the ammonium chloride occurs with the result that the pH value of the solution is raised, to temper the reaction and extend the heating period.

Various expedients can be utilized to saturate the asbestos sheets 13 with the chemical solution. It is desirable for the operator to have a small measuring device by means of which definite amounts of solution can be applied, such as a measuring dropper 22. Assuming that such a dropper or applicator is used, it is filled with a definite amount of solution, and then the solution is applied to one side of the assembly 10. The solution penetrates through the perforations to saturate both the asbestos sheets.

The pad illustrated is intended for Croquignole permanent hair waving, and it is of such a length that it can be folded, as illustrated in Fig. 2, before being applied over a conventional Croquignole curler. Thus after the asbestos sheets have been properly saturated or impregnated with the solution, the entire pad is folded over as shown in Fig. 2, and thereafter the marginal edges of the covering 11 which extend out beyond the edges of the folded assembly 10, are folded over as a safety precaution against leakage of solution. Thus as indicated in Fig. 3, after folding over as indicated in Fig. 2, marginal edges 11a are folded over, followed by a folding over of the marginal edges 11b, as shown in Fig. 4. Obviously the precise manner or sequence in which these marginal edges are folded over is of no material consequence. The complete folded packet as shown in Fig. 4 (designated generally by number 110) is now applied over a strand of wound hair, as for example in the manner illustrated in Fig. 7. In this instance a strand of hair is shown wound 70 about the Croquignole curler 23, carried by the Croquignole protector 24. The folded packet 110 is retained about the wound strand by suitable means such as the spring clip 25.

It is to be understood that in using the chemical pad described above, the wound hair is mois-

tened with aqueous waving solution, in the same manner as now practiced in conventional permanent hair waving. It is also to be understood that the dimensions of the pad can be varied to suit different requirements, as for example to enable application of the pad to a strand of hair wound about an extended rod spiral fashion, as is well known by those skilled in the art.

Shortly after applying the chemical solution to the sheets of asbestos, the exothermic reaction commences, and by the time the folded packet has been applied about the wound hair, heat is being developed to transfer heat to the wound hair. The temperature of the hair is rapidly elevated to steaming temperature, and the steaming period 15 is extended over a sufficient period of time to lend permanency to the wave. During this heating period the aluminum foil is substantially entirely consumed by the chemical reaction.

Reference has been made to the use of non-inflammable material to retain the chemical solution. Also it has been pointed out that the solution makes use of an active oxidizing agent, like sodium chlorate. At the end of the waving operation at least a part of this oxidizing agent is still present. If the sheets 13 were made of ordinary absorbent paper, or like material, impregnation of the cellulose fiber with the oxidizing agent would produce a highly inflammable article, and thus create a fire hazard. Such a fire hazard is 30 entirely avoided by the use of an inert non-inflammable fiber like asbestos, thus making it possible for the operator to discard the pads after they have been used, without particular care as to the manner of their disposal.

The perforations which are provided for the inner assembly 10, perform several desirable functions. Perforating the asbestos sheets 13, facilitates saturation of these sheets with the chemical solution. Perforating the aluminum sheet 13 augments the edge area of the aluminum foil 40 which is exposed to the chemical solution. I found that such an increase in the edge area facilitates carrying out the desired exothermic reaction. Also because of the small size of the perforations in the aluminum foil 12, these perforations tend to trap drops of solution, thus assisting retention of solution within the assembly 10, and in addition they make it possible to saturate both sides of the assembly with application of solution to only one side. Carrying out the perforating operation in the manner previously described, also tends to cause sheets 13 to adhere upon opposite sides of the aluminum foil, so that the side surfaces of the aluminum foil are retained in physical contact with the asbestos sheets.

It will be evident that my pad obviates the disadvantages previously outlined, with respect to pads making use of a foil envelope containing powdered or granulated chemicals. There can be no deterioration upon exposure to the atmosphere, because the chemical solution can be kept in well stoppered bottles, out of contact with the air at all times. Manufacture is a comparatively simple operation, which does not involve the handling of powdered material, and does not involve the making of an air-tight foil envelope.

The subject matter disclosed but not claimed 70 herein is disclosed and claimed in my co-pending application Serial No. 239,482, filed Nov. 8, 1938.

I claim:

1. In a chemical heating pad for permanent hair waving, a sheet of aluminum foil, and a

flexible sheet of absorbent material in contact with one side of the aluminum foil, the sheet of aluminum foil being perforated and the sheet of absorbent material being capable of retaining a chemical solution of exothermic reaction with the metallic foil.

2. In a chemical heating pad for permanent hair waving, a sheet of aluminum foil, and a flexible sheet of absorbent material in juxtaposition with one side of the aluminum foil, said sheet of absorbent material being adapted to retain a chemical solution for exothermic reaction with the aluminum foil, both said sheets being perforated to augment action of the solution upon the aluminum foil and to facilitate impregnation of the sheet of absorbent material with said chemical solution.

3. In a chemical heating pad for permanent

hair waving, a sheet of aluminum foil, and a flexible sheet of absorbent material in juxtaposition with one side of the aluminum foil, both said sheets having registering perforations, said sheet of absorbent material being adapted to retain a chemical solution for exothermic reaction with the aluminum foil.

4. In a chemical heating pad for permanent hair waving, a sheet of reactive metallic foil, and flexible sheets of absorbent material disposed upon opposite sides of the metallic foil and in juxtaposition with the same, both said sheets and the metallic foil having registering perforations, said sheets of absorbent material being adapted to be saturated with a chemical solution for exothermic reaction with the metallic foil.

FREDERICK L. REYNOLDS.
